Primary Examiner — Jennifer Rivard*(74) Attorney, Agent, or Firm* — Betty J. Zea(57) **CLAIM**

The ornamental design for a cosmetic product, as shown and described.

DESCRIPTION

FIG. 1 is a perspective view of a cosmetic product, embodying our new design;

FIG. 2 is a top plan view thereof;

FIG. 3 is a front view thereof;

FIG. 4 is a back view thereof; and,

FIG. 5 is a side view thereof.

The broken lines immediately adjacent the cosmetic product illustrate the bounds of the claim. The remaining broken lines illustrate the environment. None of the broken lines forms part of the claimed design. The top views and bottom views are identical; therefore bottom views have been omitted. The stippled and non-stippled portions that appear in the perspective views and the front views indicate a contrast in color.
